C. D. BEDWIN

VALVE FOR AUTOMATIC WATER HEATERS

Filed Feb. 1, 1922

UNITED STATES PATENT OFFICE.

CLARK D. BEDWIN, OF LONG BEACH, CALIFORNIA.

VALVE FOR AUTOMATIC WATER HEATERS.

Application filed February 1, 1922. Serial No. 533,371.

To all whom it may concern:

Be it known that I, CLARK D. BEDWIN, a citizen of the United States, residing at Long Beach, in the county of Los Angeles and State of California, have invented certain new and useful Improvements in Valves for Automatic Water Heaters; and I do hereby declare the following to be a full, clear, and exact description of the invention, such as will enable others skilled in the art to which it appertains to make and use the same.

My invention relates to water heaters and more especially to safety check valves for use in automatic water heaters of a type set forth in my pending application filed October 19, 1920, and bearing Serial Number 418,019.

Automatic water heaters of the type where-
20 in the flow of the gas is controlled by the manipulation of the spigot or faucet at a distance from the heater, require in addition to the usual automatic cut-off, a further safety controlling device to insure the closing of the
25 gas valve when the flow of the water is stopped. Injury to the water meter, the gas heater, and the household property is sometimes caused by the automatic actuating piston sticking and failing to cut off the flow
30 of gas after the spigot or faucet has cut off the flow of water. This injury is caused by the high back pressure produced in the water line through the continued burning of the gas flame.

35 It is an object of my invention to utilize this back pressure and effect the closing of a valve whereby the back pressure is prevented from entering the water line, and directed in full strength against the automatic actuating piston insuring the movement of said piston and the closing of the gas valve.

Another object of my invention is to produce an automatic controlling means for water heaters, said means including a special
45 ported pressure cylinder having a simple and easily accessible regulating valve, and a safety check valve associated therewith, all of said parts being effectively located beneath the heater and capable of being readily inspected and repaired.

A further object of this present invention is to locate and arrange the safety check valve within the automatic valve controlling device.

55 With these and other objects in view the invention further consists in the construction

and arrangement of the safety valve and associated parts hereinafter described and pointed out in the appended claims.

In the accompanying drawings wherein 60 similar reference characters designate corresponding parts in the several views:—

Figure 1 is a sectional elevation of my improved automatic water heater illustrating the safety check valve; 65

Figure 2 is an enlarged vertical sectional view through a portion of the automatic controlling means including the pressure cylinder, actuating piston, regulating valve and safety check valve; 70

Figure 3 is a vertical transverse sectional view partly in elevation, on the line 3—3 of Figure 2; and

Figure 4 is a detail view of the valve operated by the actuating piston for controlling the flow of gas. 75

Referring to the drawings, I have shown an automatic water heater 1, provided with the burner 2, and an automatic valve controlling device 3 located beneath the burner 80 and operatively controlled by the flow of the water. The heater may be of any preferred type, but I have shown for purposes herein a construction which includes oppositely arranged headers 4 and 5 into which are expanded opposite ends of water circulating tubes 6. Complementary plates 7 and 8 having projecting fins 9 are positioned against the headers, thereby forming a series of intercommunicating chambers adapted to direct the flow of the water through constricted water passageways while being heated. 85

The water inlet to the heater is shown at 10 and the outlet from said heater at 11. The water enters the inlet 10 and circulates through the intercommunicating chambers, leaving the heater through the outlet 11, as will be understood. 90

Communicating with the inlet chamber 10 is a water connection in the form of a vertically disposed pipe 12, the lower end of which is connected with a cylinder 13 of an actuating device or motor 14. 100

The motor 14 comprises a piston 15 horizontally movable in the pressure cylinder 13, and provided with a relatively long piston rod 16 adapted to extend beneath the heater within a suitable housing or casing 17 and operate the gas valve 18. The housing 17 105 consists of a short tubular casing detachably secured at 19 to a boss extending from the cylinder. The opposite end of the hous- 110

ing 17 is similarly secured at 20 to one end of a centrally located gas reservoir or chamber 21. Stuffing boxes 22 are provided to permit of the reciprocating of the piston rod 16 without leakage, as will be understood.

Extending upwardly from the chamber 21 is a pipe connection 23 adapted to convey the gas in a direct manner to the burner 2, which as shown herein is of a multi-tube construction, but which may be of any other approved design as will be understood.

The gas valve 18 is located at one end of the gas chamber 21 and is seated against the tubular extension 24 as shown by means of a spring 25 interposed between the valve and the end wall 26 of a casing 27. Perforations 28 are provided in the end wall 26 through which the gas enters the casing 27 prior to being admitted to the chamber 21. Any form of gas pipe connection 29, shown in dotted lines, may be threaded upon the casing 27, said connection being in communication with any suitable source of gas supply. A pilot 30 is provided for the burner 2, said pilot consisting of a relatively small vertical pipe 31, adapted to convey a small quantity of gas from the chamber 21 to the burning end 32.

Positioned beneath the aforesaid described parts is a water connection arranged in the form of a horizontally disposed pipe 33 which is connected to any suitable source of water supply. Arranged within and between the said water connection, and adjacent to cylinder 13 is a valve 34 adjustably mounted with respect to a water inlet provided in the cylinder 13 upon one side of the piston 14.

This valve 34 is provided with a threaded stem 35 and is suitably squared at its end to provide for the movement of the valve toward and away from its seat for the admission of a predetermined amount of water to the cylinder 13.

The opening 36 and the opening in the pipe connection 12 are in vertical alinement as shown for permitting the direct flow of the water through the cylinder into the heater, thereby permitting of a sensitive and instantaneous actuation of the piston 15 upon increase or decrease of the pressure of water within the cylinder 13. The direct passage of the water through the cylinder also serves to flush the cylinder and reduce to a minimum the possibility of the piston sticking on account of accumulation of sediment.

The safety check valve is shown as located in the path of the water as it passes through the opening 36, and comprises a ball valve 37 adapted to normally rest upon the valve seat as shown. Surrounding the valve 37 is an extension or cage-like structure 38, of a height sufficient to prevent the displacement of the valve. The spring 39 surrounding the

piston rod 16 and interposed between the piston 15 and one end wall of the pressure cylinder 13, serves to prevent the ball from being forced out of the cage 38. Openings 40 for the passage of the water are provided in the cage 38, these openings being best shown in Figure 3.

As shown the controlling valve 34 and the safety check valve are arranged in close proximity to each other, the inner and outer faces of the wall of the cylinder 13 forming the respective seats for the valves as shown. The water as it flows through the opening 36 lifts the check valve 37 off its seat sufficiently high to permit the free and uninterrupted passage of the water through the openings 40 out into the interior of the pressure cylinder from where it passes upwardly into the pipe 12 and into the heater. It will be seen that the safety check valve does not interfere with the normal flow of the water, said valve rising to the position shown in dotted lines in Figure 2. When the flow of the water is stopped the ball drops back upon its seat. If the piston sticks and should the normal back pressure be insufficient to move the piston toward the left, it will be seen that the gas valve remains open and the burner continues to burn after the faucet or spigot has been turned off. This causes an increase in the back-pressure and as the check valve is seated, this back pressure is exerted directly upon one side of the piston 15, causing said piston to move and cut off the gas supply.

An opening 41 is provided in the cylinder 13, said opening serving to act as a conduit for the admission of a certain amount of water into the opposite end of the cylinder at the opposite side of the piston as will be understood. This opening 41 is provided in the wall of the cylinder 13 near the left end of the latter, and a cap 42 is fitted upon the end of this cylinder as shown.

In operation cold water enters pipe 33, a portion of the water passing through the by-pass opening 41 into one end of the pressure cylinder 13 and against the piston 15 therein, the remainder of the water passing through the valve controlled opening 36 and lifting the ball check valve 37 before entering the cylinder 13 upon the opposite side of the piston. The water continues to flow through the cylinder into the pipe 12 and thence into the heater 1, from where it passes to the pipes of the system and ultimately is stopped by the hot water spigots or faucets provided in the system. When the flow of the water is stopped the check valve gravitates back to its seat and remains there until the water is allowed to again flow through the system.

When the faucet is opened, the water pressure within the heater 1, pipe 12 and cylinder 13 is reduced. When this occurs the

head of water entering the pipe 33 and more particularly that portion of the water passing through the opening 41 forces the piston 15 toward the heater, thereby causing the 5 piston rod 16 to actuate the gas valve 18 and move it off its seat. Gas is now permitted to flow into the chamber 21, thence through the pipe connection 22 to the burner 2 where it is ignited by the pilot 30. The ball check 10 valve is lifted by the flowing water and is kept off of its seat as long as the faucet or spigot remains open.

When the faucet is closed the pressure within the pipe 12 and cylinder 13 is again 15 raised, thereby causing the pressure upon both sides of the piston 15 to equalize, whereupon the springs 25 and 39 act to close the gas valve 18. The ball check valve sinks upon its seat when the faucet is closed and 20 remains there until again lifted by the flow of the water.

It sometimes happens that the piston 15 cannot be moved by the back-pressure produced when the faucet is closed, and in this 25 case the gas remains on and overheating of the device results, frequently with attending serious injury to the apparatus and adjacent property. With the safety check valve however, it will be seen that any increase 30 in the back pressure serves only to more securely seat the said check valve and prevent the escape of the back pressure into the line where it might do considerable damage. This back pressure begins to increase 35 until sufficiently strong enough to effect the movement of the piston and close the gas valve 18, said back pressure acting directly upon the face of the piston. In this manner a jammed or sticking piston is caused to 40 move in a comparatively short time after the faucet has been closed, insuring the closing of the gas valve before any damage is done.

Changes in the construction and arrangement 45 of the several parts may be made without departing from my invention, which I now particularly set forth as follows:

I claim:

1. In an automatic water heater the combination 50 with a burner of a fuel supply valve, an automatic controlling means for said valve, said means including a pressure cylinder and piston movable therein, a valve controlled water inlet for said cylinder and a check valve in said water inlet for arresting the backward flow of the water and permitting the formation of excessive back pressure for operating the aforesaid piston to close the fuel valve.

60 2. In an automatic water heater the combination with a burner of a fuel supply valve, an automatic controlling means for said valve, said means including a pressure

cylinder having spaced water inlet ports upon one side thereof and a water outlet 65 port substantially aligned with one of the said inlet ports, a piston movable in said cylinder between the said inlet ports, means connecting the piston with the fuel valve, a valve for the one of said water inlet ports which is 70 substantially aligned with said outlet port, and a valve arranged between the last mentioned inlet port and the outlet port for arresting the backward flow of the water and permitting the formation of excessive 75 back pressure against one side of the piston for closing the fuel valve.

3. In an automatic water heater the combination with a burner of a fuel supply valve, an automatic controlling means for 80 said valve including a pressure cylinder and piston movable therein, water inlets for said cylinder upon each side of the piston, a water outlet opening from said cylinder, and a check valve for one of said water inlets arranged to arrest the backward flow of water for permitting the formation of a relatively high back pressure against one side of the piston for positively closing the fuel valve.

4. In combination, a liquid container, a burner for heating the same, a fuel conduit for conveying gaseous fuel to the burner, a fuel control valve arranged in said conduit for regulating the fuel fed to said burner, a piston chamber, a piston arranged in said chamber, means connecting said piston to said fuel control valve to permit the piston to open and close said valve, a liquid supply pipe for feeding liquid to said chamber at one side of said piston, a conduit for conveying liquid from the liquid supply pipe to said chamber and at the opposite side of said piston, a liquid discharge pipe connecting the portion of said chamber at the first mentioned side of said piston to said liquid 100 container, and an automatically operating check valve arranged in the liquid supply pipe and adapted to close under back pressure in said chamber to permit the back pressure to actuate the piston and close the fuel 105 control valve.

5. A combination as claimed in claim 4 including a manually controlled valve for regulating the liquid passing through the liquid supply pipe.

6. A combination as claimed in claim 4 including springs cooperating with the piston and with the fuel supply valve for aiding in closing the fuel supply valve.

In testimony whereof I affix my signature, 120 in presence of two subscribing witnesses.

CLARK D. BEDWIN.
